US00D508819S

(12) **United States Design Patent** (10) Patent No.: **US D508,819 S**
Mangla et al. (45) Date of Patent: **** Aug. 30, 2005**

(54) **COVER FOR A CONTAINER**

(75) Inventors: **Raj K. Mangla**, Pittsford, NY (US); **J. Scott Dellinger**, Buffalo Grove, IL (US); **Mark A. Erickson**, Lindenhurst, IL (US); **Thomas J. Hayes**, McHenry, IL (US); **Suzanne R. Maslach**, Pittsford, NY (US); **Mark E. Spencer**, Gurnee, IL (US)

(73) Assignee: **Pactiv Corporation**, Lake Forest, IL (US)

(**) Term: **14 Years**

(21) Appl. No.: **29/104,994**

(22) Filed: **May 14, 1999**

(51) LOC (8) Cl. **07-99**

(52) U.S. Cl. **D7/391**; D7/392.1

(58) Field of Search D9/430, 435, 524, D9/425, 423, 424; D7/391, 392.1, 538, 542, 601, 602, 610; 220/782, 23.6, 475, 787, 556; 312/322; 229/406

(74) Attorney, Agent, or Firm—Jenkens & Gilchrist

(57) **CLAIM**

The ornamental design for a cover for a container, as shown.

DESCRIPTION

FIG. 1 is a perspective view of a cover for a container showing our new design;

FIG. 2 is a right side elevational view of the cover for a container; the left side elevational view being a mirror image thereof;

FIG. 3 is a front elevational view of the cover for a container; the rear elevational view being a mirror image thereof;

FIG. 4 is a top plan view of the cover for a container; and, FIG. 5 is a bottom plan view of the cover for a container.
